UNITED STATES PATENT OFFICE

THOMAS J. STEARNS, OF BOSTON, MASSACHUSETTS, ASSIGNOR TO ROXBURY CARPET COMPANY, OF SAME PLACE.

DESIGN FOR CARPET.

SPECIFICATION forming part of Design No. 12,046, dated November 30, 1880.

Application filed October 19, 1880. Term of patent 34 years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

The design is composed of a ground or body having straight lines arranged to represent interwoven strips or basket-work and detached independent sprays of leaves and flowers arranged as shown upon the ground-work.

This design may be used in stair-carpets with the addition of a suitable border 15

I claim—

The design for carpets, substantially as shown and described.

In testimony whereof I have signed my name to this specification, in the presence of 20 two subscribing witnesses, this 13th day of October, 1880.

THOMAS J. STEARNS.

Witnesses:

DAVID MCNAIR,
WILLIAM SCHMIDT.
